FOOT SCRAPER

Fred T. Mayers, Wichita Falls, Tex.

Application June 2, 1937, Serial No. 146,040

1 Claim. (Cl. 15—237)

This invention relates to improvements in foot scrapers, of a type that it may be placed at the side of a walk or other desired place when needed and conveniently removed when not in use, there-
5 by eliminating a hazard and danger due to its continual presence.

An object of the invention is to provide a foot scraper of few parts which may be compactly assembled for shipment without the necessity of
10 additional pieces to bind the parts together for shipping.

Another object of the invention is to provide a foot scraper upon which the bottoms and sides of the soles of the shoe and the upper may be
15 scraped free of mud.

A preferred embodiment of the invention is illus-
trated in the accompanying drawing, in which:

Fig. 1 is a sectional perspective view of a sec-
tion of side walk with the improved scraper in-
20 stalled at the side thereof;

Fig. 2 is a front elevation of the invention with
the stake attached;

Fig. 3 is a top plan view thereof; and

Fig. 4 is a front elevation of the scraper with
25 the parts assembled for shipment.

With more detailed reference to the drawing, the numeral 7 represents a scraper bar integral with and upstanding from a base 8 extending at right angles thereto, which parts are preferably
30 stamped from sheet metal and constitute the body portion of the scraper. A cut-away opening 9 is formed in the body portion to lighten the weight of the scraper and at the same time provide an upper edge on which the toe or top portion of the
35 shoe may be cleaned.

A stake 10 has an angular portion or bracket
10' which may be secured to the scraper base 8
by a bolt 11 to permit installation of the scraper

adjacent an edge of a walk 15 or the like. For convenience in shipping the stake 10 may be secured directly to the base 8 by placing the bolt
11 through hole 12 in the stake 10. The stake
10 may be pointed at 13 to permit easy insertion
5 into the ground 14 by the side of the walk 15. When desired, the stake 10 may be dispensed with
and scraper base 8 secured directly to a flat sur-
face, such as the top of the walk 15 by the use
of screws through holes 16 in the scraper base. 10

This provides a scraper involving only two main parts, the scraper portion and the stake. These parts may be assembled as shown in Fig. 4 with the stake 10 attached directly to the base 8 of the scraper by the bolt 11, which provides com-
pactness for shipment and without the necessity
of special parts for packing. When it is desired
to assemble the parts for use, the stake 10 is de-
tached by removing the bolt 11, and said stake is
turned to the position shown in Figs. 1 and 2
15 with the bracket 10' overlying the base 8 and
secured thereto by the bolt 11. Then the stake
may be inserted into the ground, preferably at
an edge of a walk, step, etc., as shown in Fig. 1,
with the base 8 overlapping the walk, providing a
20 secure mounting for the scraper. When the
scraper is not needed, it may be withdrawn readily
and withdrawn so as to eliminate a hazard and
danger due to its continued presence. 25

I claim:

A foot scraper comprising a scraper body hav-
ing an upstanding scraper bar and a relatively
flat base at an angle thereto, a stake having an
angular bracket portion arranged in overlapping
relation with the base, and means for securing
30 said bracket portion directly to the base. 35
